UNITED STATES PATENT OFFICE.

VERITA BELLE BROCK, OF BRIDGEPORT, TEXAS.

SHEET-PLACING MACHINE.

Application filed May 18, 1921. Serial No. 470,619.

To all whom it may concern:

Be it known that I, VERITA BELLE BROCK, citizen of the United States, residing at Bridgeport in the county of Wise and State 5 of Texas, have invented certain new and useful Improvements in Sheet-Placing Machines, of which the following is a specification.

This invention relates to new and useful 10 improvements in pushing and pulling devices and which is particularly adapted for placing sheets of metal in their correct relationship upon oil tanks for forming the roofs thereto.

15 An important object of the invention is to provide a device of the above nature which is constructed in a manner whereby it may be easily manipulated from a point adjacent the side of the tank so that the worker may 20 operate the device and correctly position the sheets without fear of injury.

Another object of the invention is to provide a pushing and pulling implement the arrangement of the parts being such that 25 the object adapted to be adjusted thereby may be shifted both longitudinally and laterally of the device.

A further object of the invention is to 30 provide an implement of the above nature including a pair of relatively adjustable members one of which is equipped with means for shifting the other in either direction.

35 Other objects and advantages of the invention will become apparent during the course of the following description.

In the accompanying drawings forming a part of the application and wherein like numerals are employed to designate like 40 parts throughout the several views,

Fig. 1 is a plan of the invention in use.

Fig. 2 is a transverse section of the device taken on the line 2—2 of Fig. 1.

Fig. 3 is an enlarged fragmentary bottom 45 plan of a part of the device.

Fig. 4 is a transverse section of the device taken on the line 4—4 of Fig. 1.

In the past, great difficulty has been experienced in correctly positioning the sheets 50 of steel upon the tops of oil tanks to provide

covers therefor, inasmuch as it has been accomplished by the mechanics pushing the sheets into position with long poles. With such crude tools it has been found exceedingly difficult to effect the proper positioning of the sheets and especially aligning corresponding openings in adjacent plates whereby they may be riveted together. Furthermore, the old method of positioning the sheets exposes the mechanics to increased liability of becoming injured.

With my present device, placement of the sheets of steel becomes an easy matter and may be effected accurately, quickly and without the possibility of the mechanics becoming injured. In the drawings wherein I have illustrated the preferred embodiment of my invention, the numeral 5 designates an oil tank, approximately one half the top of which is shown in Fig. 1. The upper rim 6 of the tank is indicated by the numeral 6 and is provided with a plurality of spaced apertures 7 for the insertion of rivets as will be more clearly pointed out hereinafter. A plurality of sheets of metal 8 of more or less 75 triangular form are provided to form the top of the tank by positioning them so that their apices meet at a central point 9 and the edges of the plates opposite the apices rest upon the rim 6 of the tank. The three marginal edges of each sheet of metal are provided with a plurality of spaced apertures 10 which are for the purpose of receiving 80 rivets for securing the plates upon the top of the tank.

85 My invention consists in the provision of a tool for properly and easily positioning the various sheets and embodies a pair of relatively movable members 11 and 12. The member 11 I will designate as the anchoring 90 member which consists of an elongated bar having its intermediate portion provided with an offset 13 which provides a depression or recess in the upper face of the member. The outer end 14 of this anchoring 95 member is provided with an integral loop as clearly seen, and from the marginal edges of said loop depend a pair of anchoring pins 15 as clearly seen in Fig. 4.

An operating lever 16 is adapted to be 100

seated and pivoted within the offset portions 13 of the anchoring member in a manner that both ends of the lever project beyond opposite sides of the anchoring member. 5 However, as clearly seen, one end of the lever forming the handle of the device extends further to one side of the member 11 than the other end of the lever so that the handle will be disposed adjacent the rim of 10 the tank in a convenient place for the mechanic to operate the device. To this operating lever upon opposite sides of the anchoring member are pivoted a pair of crescent shaped pawls 17, the free ends of 15 which are offset from the planes of the pawls for a purpose which will become obvious. Secured to the lever beyond each pawl are spring contained casings 18 through the inner relative end of each of which is mounted 20 a pawl engaging element 19 which is normally urged into engagement with its respective pawl by means of a coil spring surrounding the element within the casing and bearing against one end of the casing. The end of 25 each pawl engaging element is arcuated as clearly seen in Fig. 3 and the pawl engaging element being rotatable may be reversed or shifted to engage its respective pawl at either side of the pin pivoting the pawl to 30 the operating lever.

The member cooperating with the anchoring member and which is longitudinally adjustable therealong, consists of an elongated bar 12 having rack teeth 20 disposed along 35 opposite longitudinal edges thereof for co-operation with the pawls 17. The member 12 at opposite ends thereof is provided with guides 21 which in the present instance form integral oppositely disposed fingers which 40 are bent up and over the anchoring member 11. However, it is to be noted that the engagement of the guide means 21 with the anchoring member is such as to permit the member 12 to freely slide upon the member 45 11. The outer end 22 of the adjustable member 12 is bent to extend at approximately right angles and is arranged in the same plane with the member 12. The terminal of 50 this angularly disposed end is equipped with a loop 23 corresponding with the loop of the anchoring member and is provided with a pair of depending integral pins 24 adapted for the reception in the openings 55 along the edges of the sheet steel plates 8. From the foregoing description, it will 60 be seen that when the pins 15 of the anchoring member are inserted to a pair of the openings 7 in the rim of the tank and the pins 24 of the angular arm 22 are associated 65 with a pair of openings in one of the sheets and the operating lever 16 reciprocated in the well known manner, the two members 11 and 12 will move longitudinally. If the pawl engaging elements 19 are disposed in 70 the position shown in Figs. 1 and 3, the

pawls will be caused to engage the rack teeth 20 of the member 12 and upon the reciprocation of the lever will cause the member 12 to move toward the inner end 75 of the anchoring member 11. Consequently if the pins of the two members are associated with the tank heretofore set forth, it will be obvious that the sheet 8 will be shifted until its apex meets the apices of the other plates at the point 9. Should it 80 be desired, to shift the sheet 8 laterally toward its adjacent sheet, it will be obvious that one of the pins 15 of the anchoring member may be disengaged from its opening in rim and the entire device swung upon the 85 other pin 15 as a pivot which remains in engagement with the rim of the tank. Should it be desired to shift the sheet outwardly of the rim of the tank, the two pins 15 of the anchoring member are again engaged with the opening in the rim and the pawl engaging elements reversed to cause the ends of the pawls adjacent the loop 14 to engage with the rack and upon 90 reciprocation of the operating lever shift 95 the member 12 outwardly upon the anchoring member 11.

The foregoing description and accompanying drawings have reference to what might be considered to be the approved or 95 preferred form of my invention. I desire it to be understood that I may make such changes in the construction, combination and arrangement of parts, materials, dimensions, etc., as may prove expedient and fall within 100 the scope of the appended claims.

Having thus described my invention what I claim as new and desire to secure by Letters Patent is:

1. A sheet placing device comprising an 105 anchoring member, and means adjustable thereon for positioning a sheet laterally of said anchoring member.

2. A sheet placing device comprising an 110 anchoring member; a sheet engaging member adjustable on said anchoring member and said sheet engaging member having its sheet engaging end directed laterally.

3. In a sheet metal placing device comprising a pair of relatively adjustable members 115 slidably mounted one upon the other, a loop formed on the end of one member, an angularly disposed arm formed on the opposite end of the other member, a loop formed on the arm, and means for adjusting 120 the members relative to one another.

4. A sheet placing device comprising a pair of relatively adjustable members one of which is provided with a rack, a lever carried by the other member, a pawl pivoted 125 between its ends and adapted for engagement with said rack, and a reversible pawl engaging element adapted to be shifted to engage said pawl at either side of its pivot.

5. A sheet placing device comprising a 130

pair of relatively adjustable members slideably associated, and a depending pin carried by the free end of each member.

6. A sheet placing device comprising a pair of relatively movable members, means for shifting one of the members upon the other in either direction, one of said members having its free end angularly disposed to extend laterally thereof in the same plane

therewith, and integral pins carried by the free end of said member.

In testimony whereof I affix my signature in the presence of two witnesses.

VERITA BELLE BROCK.
